Alvin W. Wentz and Clara N. Watkins,
St. Louis, Mo.

Application December 26, 1940, Serial No. 97,618

Term of patent 14 years

To all whom it may concern:

Be it known that we, Alvin W. Wentz and Clara N. Watkins, citizens of the United States of America, residing in the city of St. Louis, State of Missouri, have invented a new, original, and ornamental Design for a Wheeled Chair, of which the following is a specification, reference being had to the accompanying drawings, forming a part thereof.

Fig. 1 is a plan view of a wheeled chair showing our new design;

Fig. 2 is a side elevational view;
Fig. 3 is an inverted plan view;
Fig. 4 is a front elevational view;
Fig. 5 is a rear elevational view; and
Fig. 6 is a perspective view of the same.
We claim:
The ornamental design for a wheeled chair, as shown.

ALVIN W. WENTZ.
CLARA N. WATKINS.
